UNITED STATES PATENT OFFICE

CARLETON W. CAMPBELL AND SIDNEY J. COOK, OF DENVER, COLORADO, ASSIGNEES TO
BURNAIR, INC., OF DENVER, COLORADO

GAS BURNER

Application filed July 29, 1930. Serial No. 471,460.

Our invention relates to gas burners. An important object of the invention is to provide a simple and practical gas burner that will produce a maximum of heat from the 5 gas consumed.

Another object of the invention is to provide a unit heater of the character mentioned that can be easily manufactured and installed, and which may be used in any style 10 or shape of furnace.

A further object of the invention is to provide means to pass an air stream through a flame of burning gas to afford complete combustion of the gas.

Another object of the invention is to dispose our burners in such a way that they project flames toward the vertical wall of a water jacket adjacent the bottom thereof.

Still another object of the invention is 20 to provide means to direct all of the air, passing through the furnace grate, to and through the burners thereon.

Other objects reside in details of construction and in novel combinations and arrangements of parts, which will more fully appear in the course of the following description.

In the drawing, like reference characters 30 designate similar parts in the several views. Figure 1 is a horizontal section of a furnace to which embodiments of our invention have been applied.

Figure 2 is a broken, vertical section taken on the line 2—2 of Figure 1.

Figure 3 is an enlarged elevation of an 35 embodiment of our invention, with the housing partly broken away.

Figure 4 is a cross section taken on the line 4—4 of Figure 3.

Figure 5 is a broken, diagrammatic sketch 40 of the face of a furnace, to which the invention has been applied.

Referring more in detail to the drawing, the reference numeral 6 designates generally 45 a furnace to which the present invention has been applied. The flue is shown at 7. The furnace has a sectional water jacket 8 on the sides and back. Inlets 9 are shown near the bottom of the jacket for the admission of 50 cold water into the jacket. An outlet 10 is

shown for the water that has been heated by the gas burners, hereinafter to be described.

A grate 12 is supported within the furnace, and the furnace has a door 13 for the combustion chamber. The furnace normally has 55 an ash chamber 14 below the grate 12. In the present invention, the chamber 14 is for the introduction of air to the gas burners, rather than for ashes. The wall of this chamber is indicated at 15. An opening 16 60 for the ash chamber is usually closed by a door, but with the present invention no door needs to be used.

Disposed on the grate 12 are gas burner units 17 connected in series by a gas supply pipe 18 resting on the grate. A plug 19 is disposed in the end of the gas pipe after it supplies gas to the last unit 20. It seems apparent without further illustration, that one or more units may be connected with 65 70 separate supply pipes. The pipe 18 is generally introduced into the furnace through a so-called clinker door 56.

After the units are connected and placed in position, the portion of the grate surface 75 not covered by them is closed by means of plastic material 22, preferably non-combustible. The plastic material conforms with the contour of the burner units, so that all the air ordinarily passing through the grate 80 12 will have to pass through the burner units. The plastic material may be cement, plaster, asbestos, plaster, or the like.

Each unit comprises a housing 23 having a slotted gas port 24, and a slotted secondary 85 air port 25 on a sloping surface 26 of the roof of the unit. The air port 25 is so disposed that it directs an impinging stream of air against the flame coming from the gas port 24.

The housing contains longitudinal partitions 27 and 28 providing a gas and air mixing chamber 29. The gas port 24 is disposed lengthwise of the mixing chamber 29. The partition 27 is spaced from an upright wall 30 of the housing to provide an elongated air 90 95 chamber 31 that feeds air to the port 25.

The mixing chamber 29 has a cuplike depression 32 at the gas inlet. A space 33 in the housing below the mixing chamber provides another air chamber. The supply pipe 100

18 passes through an opening 34 in the housing and into the air chamber 33. A T coupling 35, connected with the pipe 18, carries a gas injector designated generally by the character 36.

5 The injector has an integral screw plug 37 that screws into a threaded outlet 38 of the T coupling. An adapter 39 is disposed in the

10 plug and provides a restricted orifice 40 for the escape of gas from the pipe 18 into the injector 36. It seems clear that to increase or decrease the capacity of the burner, it is only necessary to provide an adapter having a larger or smaller orifice.

15 The injector has an inner tube 41, the passage of gas through which causes the primary or initial supply of air to be drawn through an opening 42 of the inner tube. The inner tube projects into an outer tube 43 and is integrally connected thereto, as shown at 44. The outer tube has sections 45 and 46 of different diameters connected by a tapered portion 47. The exterior of the section 45 is slightly tapered exteriorly to provide a close fit between the injector and inlet 48 of the mixing chamber 29. In fact, it is often preferred to have the tapered section 45 of the injector support the entire housing 23 and its associated parts.

20 The section 46 has lateral air inlets 49 to supply air from the spaces 33 to the interior of the outer tube 43, to pass with the gas into the mixing chamber 29.

25 In the operation of the invention, after the units are connected with the gas supply 18 and placed in position, the grate surface, exterior of the units, is covered over with the plastic material 22, which forms an air tight joint with the unit housings.

30 Gas is then introduced into the supply pipe and ignited at the port 24. Air is mixed with the gas at three different points, to wit, first, in the inner tube 41, second, in the outer tube 43, and, third, at the point of combustion as indicated by the arrows 50. As the gas enters the mixing chamber, it expands, as shown by the arrow 51 in Figure 3.

35 It will be noted that the gas port 24 is not at the peak 52 of the housing roof, but it is at one side thereof. The advantage of this arrangement is that slope of the roof, as shown at 53, causes a turbulence of the gas as noted by the arrows 54. By this means a more thorough mixture of the gas and air is obtained.

40 As stated, the secondary air emitted from the port 25 impinges upon the gas escaping from the port 24. The burner units are so disposed that the burning gas is projected upon the lower part of the water jacket 8, to heat and circulate the water therefrom through the heating system.

45 It is to be understood that changes may be made in the construction and arrangement

of parts without departing from the spirit and scope of the present invention.

It is to be understood without further illustration that the present invention is not limited to use in a hot water heating plant, but may be used in hot air furnaces and stoves; in fact, wherever gas heat may be utilized.

What we claim and desire to secure by Letters Patent is:

1. A gas burner comprising a housing partitioned to provide an upper mixing chamber and a lower air chamber having an upwardly ejecting air outlet, the mixing chamber having a gas outlet discharging across the path of the upwardly ascending air, whereby to effect a mixing of the air and gas after issuance from the burner housing, a gas injector set in the partition separating the mixing and air chambers, and means for supplying gas to the injector.

2. A gas burner comprising a housing partitioned to provide an upper mixing chamber and a lower air chamber having an upwardly ejecting air outlet, the mixing chamber having a gas outlet discharging across the path of the upwardly ascending air, whereby to effect a mixing of the air and gas after issuance from the burner housing, a gas injector set in the partition separating the mixing and air chambers, and comprising an outer tube having lateral air inlets in its lower portion, and an inner upwardly tapered tube opening at its lower end into the air chamber, and means for supplying gas to the lower end of the inner tube.

3. A gas burner comprising a housing having a sloping top portion in which are formed upper and lower outlets, and partitioned to provide an upper mixing chamber connecting with the upper outlet and a lower air chamber connecting with the lower outlet, a gas injector set in the partition and comprising an outer tube having lateral air inlets in its lower portion, and an inner upwardly tapered tube opening at its lower end into the air chamber, and means for supplying gas to the lower end of the inner tube.

4. A gas burner comprising a housing having a sloping top portion in which are formed upper and lower outlets, and partitioned to provide an upper mixing chamber connecting with the upper outlet and a lower air chamber connecting with the lower outlet, said partition having a centrally disposed cup-shaped depression, an injector set in the depressed portion of the partition and comprising an outer tube having lateral air inlets in its lower portion and an inner upwardly tapered tube opening at its lower end into the air chamber, and means for supplying gas to the lower end of the inner tube.

5. A gas burner comprising a housing having its top reversely sloped and having upper and lower outlets in one of the sloping

portions, and partitioned to provide an upper mixing chamber and a lower air chamber connected with the respective upper and lower outlets, said partition having a central portion depressed, an injector set in the de-
5 pressed portion of the partition and comprising inner and outer tubes, the latter having lateral air inlets in its lower portion, and the inner tube extending across the lateral air inlets and terminating a distance from
10 the top of the outer tube, and means for supplying gas to the inner tube of the injector.

In testimony whereof we hereunto affix our signatures.

CARLETON W. CAMPBELL.
